UNITED STATES PATENT OFFICE

141,555

DESIGN FOR A NURSERY BOTTLE HOLDER

Pearl F. Milks, Chicago, Ill.

Application February 14, 1945, Serial No. 117,932

Term of patent 7 years

(Cl. D83—8)

To all whom it may concern:

Be it known that I, Pearl F. Milks, a citizen of the United States, residing at Chicago, in the county of Cook and State of Illinois, have invented a new, original, and ornamental Design for a Nursery Bottle Holder, of which the following is a specification, reference being made to the accompanying drawing, forming a part thereof, in which

Fig. 1 is a side elevational view of a nursery bottle holder embodying my new design;

Fig. 2 is a plan view of the same; and

Fig. 3 is a front elevational view thereof.

I claim:

The ornamental design for a nursery bottle holder, substantially as shown.

PEARL F. MILKS.
